UNITED STATES PATENT OFFICE

2,099,437

ELECTRICAL APPLIANCE AND BASE

William H. Fischer, St. Louis, Mo., assignor to
 Knapp-Monarch Company, St. Louis, Mo., a
 corporation of Missouri

Application June 26, 1936, Serial No. 87,454

14 Claims.

(Cl. 53—5)

An object of my invention is to provide an electrical appliance and base for supporting the appliance, the base being comparatively simple and inexpensive from a manufacturing standpoint.

A further object is to provide an electrical appliance, especially of low mounted type, and a base which can be inexpensively formed yet which is durable and which is particularly adapted for mounting the appliance in a low position with respect to a table top or other supporting surface without an objectionable amount of heat from the appliance affecting the table top.

Still a further object is to provide a low mounted appliance having a support in the form of a flat sheet of material reinforced along two opposite edges thereof by a flange or the like and reinforced along its other two edges by elongated members associated with said other two edges to support the plate substantially spaced from a table top or the like and to space the flanges thereof also above the table top.

Still a further object is to provide a supporting base in the form of a plate and a pair of members secured to opposite edges thereof, said members being grooved to receive the edges of the plate and thus reinforce it and being formed with outwardly extending flanges serving as handles by which the appliance and base may be carried.

Still a further object is to provide a base which is neat in appearance, yet effectively prevents the transmission of heat from an appliance to a table top so that the appliance can be mounted relatively low and the stability of the appliance thereby enhanced.

Still a further object is to provide a combined foot and handle member adapted to be mounted on an appliance base or the like, such member preventing any scratching of a supporting surface and at the same time provide a handle which is relatively cool.

Still a further object is to provide a combined handle and foot member which spaces a tray or base of an electric appliance from a table top, such combined handle and foot being of low heat conducting material so that there is no contact with a table top of a metallic support or the like which would permit passage of heat to the table top by conduction.

With these and other objects in view, my invention consists in the construction, arrangement and combination of the various parts of the device, whereby the objects contemplated are attained, as hereinafter more fully set forth,

pointed out in my claims, and illustrated in the accompanying drawing, in which:

Figure 1 is a perspective view of an electrical appliance and base embodying my invention.

Figure 2 is an end elevation of the same, a portion thereof being sectioned on the line 2—2 of Figure 1.

Figure 3 is a front elevation, partially in section, on the lines 3—3 of Figure 2; and

Figure 4 is an enlarged sectional view on the line 4—4 of Figure 1, showing how parts of the base are assembled relative to each other.

On the accompanying drawing I have used the reference character A to indicate generally an electrical appliance or electrically heated casing such as a sandwich toaster or the like.

A supporting base for the appliance A is indicated generally at B. The base B comprises a plate 10 and a pair of elongated elements 12 for supporting it relative to a table top or other supporting surface 14.

The plate 10 is formed of a single sheet of metal or other appropriate material and is generally rectangular in shape. Two opposite edges thereof are provided with flanges 16 which serve the purpose of reinforcements against longitudinal bending of the plate 10. These are preferably formed as rolled or tubular flanges projecting downwardly, as clearly shown in Figure 3, and are supported in spaced relationship to the surface 14 by the elongated members 12.

Any suitable means may be provided for connecting the appliance A to the central portion of the plate 10, although I preferably use the means disclosed in my Patent No. 2,040,369, issued May 12, 1936. This means consists of upwardly depressed and spaced apart portions 18 formed on the plate 10, a plurality of these being provided. On the bottom of the casing A, downwardly depressed portions 20 register with the portions 18. The two may be secured together in any suitable manner, tongues 22 of the portions 18 entering slots 24 of the portions 20 by way of illustration.

The portions 18 and 20 space the appliance A from the base B so that I secure ample air circulation between the casing and base to effectively dissipate most of the heat transmitted from the appliance A to the base plate 10.

The elongated members 12 are formed of material which is a poor conductor of heat and may be formed of wood if desired, which is relatively inexpensive. The members 12 are preferably shaped so as to have a longitudinal slot or groove 26, a downwardly extending flange 28 serving as

a supporting foot and an outwardly extending flange 30 serving as a handle. As shown in Figure 4, the ends of the sheet of material 10 are pushed into the grooves 28 as indicated by the 5 arrow a, after which a single screw may be driven home in the direction of the arrow b in a bore 34 provided therefor, a perforation 36 being provided in the edge of the plate 10 through which the screw extends, as shown in Figure 3.

10 The flange 28 of each elongated member 12 is of sufficient height to substantially space the plate 10 above the surface 14 to secure space through which air may circulate between the lower surface of the plate 10 and the supporting 15 surface 14 to dissipate the heat therefrom, the flanges 16 being spaced far enough from the surface 14, as shown in Figure 2, to permit such circulation yet give the appearance to the casual observer of resting on the surface 14. The elongated members 12 serve to reinforce the plate 10 against lateral bending and also give an ornamental appearance to the base and provide handles which may be engaged for lifting the appliance from the surface 14 and carrying it from 20 one position to another. The plate 10 is very inexpensively formed, as it is cut in rectangular shape and the only forming operations are rolling the flanges 16 and forming the projections 18.

25 The flanges 16 are very effective to prevent 30 any longitudinal bending of the plate while the elongated members 12 effectively serve the purpose of preventing lateral bending thereof when assembled relative to the plate. The elongated members 12 can be inexpensively formed in a 35 mold forming machine or the like and the manner of assembly obviously is very simple.

Some changes may be made in the construction and arrangement of the parts of my device without departing from the real spirit and purpose of my invention, and it is my intention to 40 cover by my claims any modified forms of structure or use of mechanical equivalents which may be reasonably included within their scope.

I claim as my invention:

45 1. A support for a relatively low electrical appliance comprising a single sheet of substantially flat material having flanges along two opposite sides thereof, elongated members having grooves receiving the other two sides thereof, said elongated members projecting below the lower surface of said sheet of material to form supporting feet for the material relative to a table top or the like and means spaced from said elongated members, formed of said sheet material and projecting upwardly from the plane thereof to which the relatively low electrical appliance is rigidly connected for positioning said appliance above and spaced from the sheet of material.

50 2. A support for a relatively low electrical appliance comprising a single sheet of substantially flat material having flanges along two opposite sides thereof, elongated members having grooves receiving the other two sides thereof, said elongated members projecting below the lower surface of said sheet of material to form supporting feet for the material relative to a table top or the like, said elongated elements having handle portions formed thereon and means spaced from said elongated members, formed of said sheet material and projecting upwardly from the plane thereof to which the relatively low electrical appliance is rigidly connected for positioning said appliance above and spaced from the sheet of material.

55 3. In an appliance of the character disclosed,

a plate-like supporting element, a casing element, an electrical heater for said casing element, means for connecting said elements together with a space between the major part of said elements for circulation of atmospheric air and means for supporting said plate-like supporting element spaced from a table surface or the like comprising a pair of elongated members having portions projecting below the lower surface of said plate-like supporting element, having grooves receiving the 10 two opposite edges of said plate-like supporting element and having outwardly extending portions serving as handles.

4. A support for an electrical appliance comprising a single sheet of substantially flat material having flanges along two opposite sides thereof, elongated members having grooves receiving the other two sides thereof, vertical elements extending into said elongated members and through the edges of said other two sides of said sheet of material to retain said elongated members in position relative to said sheet of material, said elongated members projecting below the lower surface of said sheet of material to form supporting feet for the material relative to a supporting surface and means spaced from said elongated members, formed of said sheet material and projecting upwardly from the plane thereof to which the electrical appliance is rigidly connected for positioning said appliance above and spaced from the sheet of material.

5. A support for an electrical appliance comprising a single sheet of substantially flat material having flanges along two opposite sides thereof, elongated members having grooves receiving the other two sides thereof, said elongated members projecting below the lower surface of said sheet of material to form supporting feet for the material relative to a table top or the like, said elongated elements having handle portions formed thereon and means spaced from said elongated members for supporting the electrical appliance rigidly on and spaced above the sheet of material.

6. A support for a relatively low electrical appliance comprising a single sheet of substantially flat material having flanges along two opposite sides thereof, elongated members having grooves receiving the other two sides thereof, said elongated members projecting below the lower surface of said sheet of material to form supporting feet for the material relative to a table top or the like and means spaced from said elongated members for securing the relatively low electrical appliance rigidly to the sheet of material.

7. A support for a relatively low electrical appliance comprising a single sheet of substantially flat material having flanges along two opposite sides thereof, elongated members having grooves receiving the other two sides thereof, said elongated members projecting below the lower surface of said sheet of material to form supporting feet for the material relative to a table top or the like, said elongated elements having handle portions formed thereon and means spaced from said elongated members for securing the relatively low electrical appliance rigidly to the sheet of material.

8. In a low mounted type electrical appliance and base, a substantially rectangular supporting plate of metallic material, flanges formed along at least two opposite edges thereof, elongated supporting members of non-metallic material associated with the other two edges only thereof for supporting said plate relative to a supporting surface, said elongated supporting

members extending throughout substantially the lengths of said other two edges, a casing, an electric heater therefor, and means for connecting said casing to said supporting plate to provide a unitary structure.

9. In an electrical appliance and base, a substantially flat plate-like supporting element, a casing element, an electric heater for said casing element, one of said elements having a plurality of laterally spaced portions projecting from the plane and formed of the material thereof and extending toward and engaging the other element for supporting purposes, said portions providing a space between the major part of said elements for circulation of atmospheric air including the space among said portions, and means for supporting said plate-like element spaced from a table surface or the like comprising a pair of elongated members substantially 20 spanning the ends of said plate-like supporting element, having portions projecting inwardly from the ends of said plate and terminating below the under surface thereof for supporting purposes, said elongated members having outwardly extending portions serving as handles.

10. A support for a low mounted electrically heated appliance comprising a single sheet of relatively flat material permanently fastened to and forming a unitary part of said appliance, said sheet 30 of material having means along two edges thereof and substantially spanning said edges for supporting said sheet of material above a table surface or the like, said means having portions projecting away from the sheet of material serving as handles for supporting said appliance by hand and portions projecting inwardly from said edges for covering said edges and serving as feet.

11. In an electrical appliance and base therefor, a substantially flat sheet metal supporting 40 plate, an electrically heated casing supported on said plate, and means for supporting two opposite edges of said plate in position with the plane of the plate spaced above a table top surface or the like, said means comprising a pair of elongated, 45 non-metallic members secured to said edges of said plate and extending substantially throughout the length thereof, said members having portions extending below said plate which cover and conceal the edges of said plate, and means closely adjacent said edges for securing said elongated members to said plate.

12. In a device of the class described, a metal supporting plate having flanges formed along at 50 least two opposite edges thereof, an electrically heated casing supported on said plate, and means for supporting the other two opposite edges of said plate spaced above a table top surface or the like with said flanges also spaced thereabove, said means comprising non-metallic, elongated ele-

ments having substantially vertical flanges to act as supporting feet for the device and as supporting flanges for said other two opposite edges of said supporting plate, and connected to conceal said two opposite edges said elongated elements 5 having substantially horizontal elements extending throughout substantially their lengths to act as supporting handles for the device.

13. In a device of the class described for supporting an electrical appliance, a substantially flat 10 supporting plate of rectangular shape having flanges formed along at least two opposite edges thereof, an electrically heated two-part hinged casing supported on said plate with the hinged part adapted to be swung to open position and 15 supported in such position with the center of gravity then shifted from the center of said two-part casing when closed, and means for supporting the other two opposite edges of said plate spaced above a table top surface or the like with 20 said flanges also spaced thereabove, said means comprising an elongated member formed of low heat conducting material fixed along each end of said plate and of such length as to substantially span the distance between said flanges in such 25 manner that said supporting plate will remain in horizontal position notwithstanding the shifting of the center of gravity when said casing is in open position, said means having portions projecting away from said plate serving as handles. 30

14. A support for a relatively low electrical appliance comprising a single sheet of substantially flat metal having flanges along at least two opposite sides thereof, an electrically heated casing having a lower part fixed to said sheet of metal 35 and an upper part hinged to said lower part and thereby adapted to be moved to an open position relative to said lower part and to be supported in such open position by the hinge connection, the center of gravity of said casing when 40 so opened shifting from the center of the casing when closed to a position adjacent the hinged connection, said center of gravity when so shifted falling between the flanged sides of said base, an elongated member of non-metallic material fixed 45 to each end of said sheet of metal and of substantially the same length as the width of the sheet of metal, said elongated members having portions fixed along the other two sides of said sheet of metal and substantially spanning said other two 50 sides, whereby said supporting plate will remain in position on a table top or the like against tipping relative thereto notwithstanding the shifting of the center of gravity when said upper part of said casing is in open position, said elongated 55 member projecting downwardly from said sheet of metal to support it relative to such table top.

WILLIAM H. FISCHER.
